Joseph Lacroix

UNITED STATES PATENT OFFICE.

JOSEPH LACROIX, OF FARIBAULT, MINNESOTA.

IMPROVEMENT IN FLOUR AND MIDDLEDGS PURIFIERS.

Specification forming part of Letters Patent No. 149,869, dated April 21, 1874; application filed April 10, 1874.

To all whom it may concern:

Be it known that I, JOSEPH LACROIX, of Faribault, county of Rice, State of Minnesota, have invented a new and useful Improvement in Flour and Middlings Purifiers, of which the following is a specification:

Figure 1 is a longitudinal vertical section of my improved machine. Fig. 2 is a top or plan view of the vibrating conveyer.

The object of my invention is to purify the middlings without separating or grading them at the same time, or with the same machine; and to remove the fine and light impurities from the middlings, either before or after their passing over a separating or grading machine. The middlings passing over the last-mentioned machines can only be partially purified, the greatest and best part of them going through at the head of the machine without having the benefit of the air-blast. It follows that, in order to obtain a perfect purification of the middlings, their whole body should be subjected to a continuous current of air without separating them gradually. The object of my invention is also to separate and grade flour by separating the light and less pure flour from the heavier and purer, the light flour being drawn off by the suction-fan and discharged into a proper receptacle, which may be re bolted and purified, if desired. My invention consists in a conveying-frame arranged in an air-tight chamber, and provided with alternate slats and transverse openings, larger than the particles of material passing over it, and through which a blast of air is forced upward in thin sheets to keep the flour or middlings from falling through said openings, and raising and carrying off the light impurities; and also in connection therewith a suction-fan to assist in removing the impurities, as will be hereinafter more fully described.

A is an air-tight chamber, in which is suspended, by links *a*, or otherwise, the conveying-frame B, operated by a double eccentric, C, or similar means. The conveying-frame B is constructed of slats D, made of zinc, tin, wood, or other suitable material, leaving transverse openings *d* between them, from one-sixteenth to one thirty-second of an inch in width, through which currents of air from a blast-fan, E, pass in thin sheets, and keep the middlings

or flour passing over the conveying-frame from falling through said openings, and also raise up and separate the light impurities to be drawn off by the suction-blast from fan F. E is a fan-blower placed in front of the machine, the blast of which is introduced into the chamber G below the conveying-frame. This air-chamber G may be constructed so as to vibrate with the conveying-frame, as clearly shown, or it may form a lower section of the main chamber with the vibrating conveying-frame suspended over it, and dividing it from said main chamber perfectly without allowing the air from the blast-fan to pass anywhere but through the transverse openings in the conveying-frame. The air-chamber G, by preference, is made decreasing in height from the opening communicating with the mouth of the blast-fan to the other end of it, as shown in Fig. 1, in order that the air shall act equally on all parts of the conveying-frame. The slats D forming the upper surface of the conveying-frame, are beveled on their under sides or edges toward the top of the transverse openings, in order to let the air through more freely and more effectually, and also, in case any flour or middlings should fall through the openings into the air-chamber below when the machine is first started, that they may be easily blown back through the same openings into the main chamber as soon as the machine is in full motion. I is a flexible tube or band connecting the mouth of the blast-fan with the air-chamber G, when said chamber is made to vibrate with and form part of the conveying-frame. This flexible tube is dispensed with when the chamber G is made stationary. F is the suction-fan, placed in the upper part of the machine to draw off the air containing the light impurities separated and raised up from the material passing over the conveying-frame by the currents or thin sheets of air from the blast-fan. *b* is an inclined hopper, from which the flour or middlings to be operated upon are fed. *b'* is an opening at lower end of the hopper *b*, regulated by a slide-valve, *b*², through which the flour or middlings pass in regulated quantity to an inclined board or plate, *b*³, which acts as the feeder, and is supported and carried by the vibrating conveying-frame in such manner that the motion of the convey-

ing-frame causes the flour or middlings supplied to the feeder to be discharged on the conveying-frame. The chamber A, at its lower part, extends over the whole surface of the conveying-frame, but decreases gradually upward toward the point A', where it opens into a narrow passage regulated by the slide c, which connects this chamber with the fan-chamber F'. The fan-shafts and eccentric shaft are all driven by pulleys and belts from any convenient power.

By this construction of conveying-frame, the flour or middlings carried over it by its vibrating movement are intermittently subjected to thin sheets of air passing up through the transverse openings from the blast-fan, which keep the material from falling through, and cause the dust and all other impurities to rise into the upper part of the main chamber, where it is subjected to the suction from, and drawn off by, the exhaust-fan F. The purified material passes over the end of the conveying-frame into any proper receptacle, or to a separator to be graded, if desired.

Fig. 3 is a modification of the conveying-frame B, in which is shown a sieve covered with tin, wood, or other suitable material, leaving spaces between them for the currents of air to pass through, in a similar manner as the form of conveying-frame shown in Fig. 2.

I do not wish to confine myself to a vibrating conveying-frame, as an inclined stationary conveying-frame, constructed in the same manner, could be used, as the inclination of the conveying-frame, assisted by the blast of air, would cause the flour or middlings to travel

toward the lower end thereof. Neither do I wish to confine myself to the use of both a blast and a suction fan. The air from a blast-fan passing upward through the conveying-frame will keep the material from falling through, and will also carry off the light impurities. I prefer, however, the use of the suction-blast in connection therewith to assist in removing the impurities.

I am aware that a blast and suction fan used in connection with a screen are old, and such I do not claim; but

What I claim as my invention, and desire to secure by Letters Patent, is—

1. In a flour or middlings purifier, the conveying-frame B constructed of alternate slats D, and transverse openings d, in combination with the blast-fan E for forcing a blast of air in thin sheets upward through the transverse openings of the conveying-frame, to keep the material from falling through, and separate and carry off the light impurities, substantially in the manner described.

2. The combination, with the vibrating conveying-frame B, provided with alternate slats D, and transverse openings d, of the blast-fan E and the suction-fan F, substantially as and for the purpose described.

3. The combination, with the vibrating conveying-frame B, and vibrating air-chamber G, of the blast and suction fans E and F, substantially as and for the purpose specified.

JOSEPH LACROLX.
